United States Patent

Des. 238,732

Patented Feb. 10, 1976

238,732

TOWEL BAR

George D. Read, Glendora, Lawrence Glen McCain,
Beverly Hills, and Edward William Scott, Culver City,
Calif., assignors to Scovill Manufacturing Company,
Waterbury, Conn.

Filed Oct. 15, 1974, Ser. No. 514,634

Term of patent 14 years

Int. Cl. D6—06

U.S. Cl. D6—99

Fig. 6.

Fig. 4.

FIG. 1 is a front elevational view of a towel bar showing our new design;

FIG. 2 is a top plan view thereof;

FIG. 3 is a rear elevational view thereof;

FIG. 4 is a side elevational view thereof;

FIG. 5 is a sectional view taken on line 5—5 of FIG. 4; and

FIG. 6 is a sectional view taken on line 6—6 of FIG. 1.

FIGS. 1, 2, 3, and 5 are shown broken away to indicate indeterminate length which tapers uniformly from the center to the extremities.

We claim:

The ornamental design for a towel bar, as shown and described.
